UNITED STATES PATENT OFFICE.

CORNELIUS CALLAHAN, OF CHELSEA, MASSACHUSETTS, ASSIGNOR TO THE AMERICAN FIRE HOSE MANUFACTURING COMPANY, OF SAME PLACE.

HOSE-CARRIER.

SPECIFICATION forming part of Letters Patent No. 251,996, dated January 3, 1882.

Application filed October 6, 1881. (No model.)

To all whom it may concern:

Be it known that I, CORNELIUS CALLAHAN, of Chelsea, county of Suffolk, and State of Massachusetts, have invented an Improvement in Hose-Carriers, of which the following description, in connection with the accompanying drawings, is a specification.

This invention has for its object the production of a cheap and efficient carrier, by which a fireman may easily carry fire-hose up a ladder or suspend it on the rounds of a ladder.

My improved hose-carrier is composed of a strong leather strap provided at one end with an open loop to embrace the strap and at its other end with a handled ladder-hook to engage the round of a ladder, all as will be hereinafter described.

Figure 1 represents in side view a hose-carrier embodying my invention, and Fig. 2 shows the same applied to and as lifting a length of hose.

A is a strong leather strap, one end of which is passed through an opening in and riveted at *a* about a bar of a rectangular metal loop, B, open at its rear end, as at *c*, to permit it to be readily and easily passed over the strap A, the latter being thus received in the space *d* of the loop, where it will be retained by the projection *e*, which forms a shoulder to receive the edge of the strap when the carrier is applied to the hose H, as in Fig. 3. The strap A at its upper end is riveted at 2 about the bar of a ladder-hook, E, having cast or formed with it a grasping-bar, 3, which is extended in the direction of the point 4 of the ladder-hook.

The ladder-hook has its point 4 extended in one direction, but the loop B is open at its rear side or in the opposite direction, which is of great advantage, because as the hose is being carried the strap is made to draw thereon in the direction of the point 4 of the ladder-hook, which direction of strain, it will be obvious, tends to maintain the strap in the central part of the loop B, whereas if the loop B were open or had the projection *e* at its opposite end the tendency of the strap would be to draw out from the loop.

I am aware that ropes have been connected with hooks to engage them when the ropes are made to encircle the hose; but the hooks differ in shape when compared with the loop B, and the hooks are not so shaped as to positively prevent the accidental escape of the ropes from the hook when under strain.

I claim—

As an improved article of manufacture, the hose-carrier composed of the strap A, the ladder-hook, and the loop B, opened at its rear side and opposite the direction of the opening of the ladder-hook and provided with a projection, *e*, to extend across the edge of the strap A and hold it in the loop, all substantially as shown and described.

In testimony whereof I have signed my name to this specification in the presence of two subscribing witnesses.

CORNELIUS CALLAHAN.
